TIMING MECHANISM

Application filed January 14, 1932. Serial No. 586,685.

This invention relates to timing mechanism which is actuated by fluid pressure from a continuous source of supply for alternately connecting and disconnecting two or more ports through which fluid under pressure flows for the actuation of devices with which such timing mechanism is associated, and more particularly the invention comprises a fluid actuated valve which embodies a dumb-bell type piston reciprocable from end to end of a chamber under the influence of the pressure of accumulated fluid exerted on the ends of such piston, with detent means for holding the piston at either extremity of its stroke until sufficient pressure has accumulated to move it to the other extremity of its stroke, and ports controlled by the piston in its movement to alternately establish and cut off communication between the source of fluid pressure and the mechanism to be operated by the intermittent application of such pressure; all as will be described more fully hereinafter, and as claimed.

In the accompanying drawing illustrating several forms of a specific embodiment of my invention;

Fig. 1 shows, partly diagrammatically and partly in cross section, the timing mechanism applied to the intermittent actuation of a valve in a pipe line;

Fig. 2 is a sectional view partly in section and partly in elevation and shows an arrangement for controlling the flow of liquid to two different points of use; and

Fig. 3 is a segmental detailed view partly in section and partly in elevation showing an arrangement for operating a small mechanical device such as counter or the like. The invention may be used for supplying a liquid or gas to apparatus at any desired time intervals, for supplying different chemicals in definite proportions to a valve or mixing chamber, and for many other uses which it is needless to here enumerate.

It will be evident from the following description that the timing may be adjusted to close limits and that an infinite number of timing combinations are possible for the reason that the time the piston of the valve

remains in one position of its stroke is wholly independent of the time it remains in its other position.

Referring more particularly to the drawing:

A pipe 10 which has connection with a source of fluid under pressure (not shown) terminates in a four-way union 11 from which branch pipes 12, 13, and 14 extend to convey the pressure fluid to reservoirs 15 and 16, and to cylinder 17 within which a dumb-bell type piston 18 is slidably retained. The piston comprises enlarged heads 19 and 20 connected by a portion 21 of reduced diameter to afford a space within the cylinder and between the heads. This space is in effect a ported chamber, varying in position but not in size.

Either or both of the piston heads 19 and 20 are formed with a pair of annular grooves 22, 23, 24, 25, into one of which a detent 26 is yieldingly pressed by a spring 27, compressed by the screw 28 which is threaded into the tubular extension 29 of cylinder 17. Obviously, the detent mechanism may be duplicated for cooperation with both heads of the piston simultaneously.

The reservoirs or pressure chambers 15 and 16 have outlets 30 and 31, respectively, communicating with the cylinder 17 at its ends, and in the inlets 12 and 14 are regulating valves 32 and 33 which may be independently adjusted to regulate the flow of pressure fluid into the respective reservoirs or chambers.

The valve cylinder 17 has vent ports 34 and 35 one of which is opened upon each stroke of the piston to alternately relieve the reservoirs 15 and 16 of pressure. Thus, when valves 32 and 33 are set to admit fluid to the reservoirs 15 and 16 at the desired rate, the accumulation of fluid in chamber 15 will overcome the inertia of the piston and at a predetermined pressure, will overcome the holding effect of detent 26 whereupon the piston will move from the position shown in the drawing to its other extreme position in which it closes vent 35 and opens vent 34 for the relief of pressure in chamber 15 while at the same time pressure is being

built up in chamber 16. Upon movement of the piston to the right as seen in the drawing the detent 26 will engage in groove 24 and will thus prevent return movement of the piston until the sufficient and predetermined pressure has been built up in reservoir 16.

Timing of the piston in its reciprocation may be regulated not only by adjustment of valves 32 and 33, but also by the capacity of the reservoirs used. Thus it is seen that the piston may be made to reciprocate rapidly or slowly and with or without regularity.

If it is desired to operate small mechanical contrivances by the reciprocation of the piston, the piston may be provided with a rod 42 extending through packing gland 43 in an end wall of the cylinder and provided with a rack 44 for engagement with a pinion gear 45 of a counting device or the like, as shown in Fig. 3.

In the form of invention illustrated, a pipe 36 is tapped into the cylinder 17 to communicate with the space around the reduced portion of the piston, and in the position of the piston shown this space is also vented by a pipe 37, the inlet 13 being closed by piston head 20.

Pipe 36 leads into a housing 38 which contains a diaphragm operating upon the application of pressure to depress a valve stem 39 and thereby to actuate the valve in pipe line 40. A coiled spring 41 holds the valve stem in contact with the diaphragm at all times.

Assuming the parts of the apparatus to be in the position shown in the drawing, air or gas under pressure from the source of supply passes through pipe 10 and into branch pipes 12, 13, and 14. Since the end of pipe 13 is closed by piston head 20 the pressure fluid will not enter cylinder 17 but will flow past valves 32 and 33, which have been cracked open the desired extent, and into reservoirs 15 and 16. From the reservoir 16 the fluid escapes through pipe 31 into the end of cylinder 17 from which it passes by way of vent pipe 35, but the fluid in reservoir 15 flows into pipe 30 and exerts its pressure upon the end of cylinder head 19. When the pressure in chamber 15 has been built up sufficiently to overcome the friction of piston 18 and the holding effect of the detent 26, the piston valve will slide to the right permitting chamber 15 to vent to the atmosphere through the end of the cylinder and pipe 34 while at the same time pressure commences to build up in reservoir 16. The pipe 13 being no longer closed, fluid under pressure will enter the space between the piston heads and by flowing into pipe 36 will exert pressure on the diaphragm in housing 38 to actuate the valve or other mechanism. When the piston again returns to its initial position, the vent pipe 37 is

uncovered to relieve the cylinder 17 and pipe 36 of pressure and, thus, permit return of the diaphragm to normal position.

In one use of the mechanism for controlling the flow of liquids (see Fig. 2) pipe 36 may be connected to a source of liquid and may communicate through the valve cylinder 17 with outlets 13 and 37. In such a structure the inlet 10 will be connected to branch conduits 12 and 14 by a T fitting 75 and will not communicate with branch 13 as in the form of invention shown.

It will be understood that in the modified apparatus the flow of liquid from pipe 36 to outlets 13 and 37 is regulated and controlled by movement of the valve 21 in its alternate movement from one end of the cylinder to the other. Flow is directed alternately to outlets 13 and 37.

If desired, the form of invention shown in Fig. 2 may also be used to supply two different liquids to a single point of use at predetermined intervals. This may obviously be accomplished by simply connecting pipes 13 and 37 to the source of supply of the liquids and connecting pipe 36 to the point of use.

From the foregoing it will be apparent that this invention provides a simple and expedient timing mechanism which in its operation is independent of the apparatus which it controls in that its action is not affected by conditions within the apparatus, and moreover that in this invention the timing may be regular or irregular at the will of the operator.

What I claim as my invention is:

1. A pneumatically operated timing device comprising a source of fluid under pressure, a cylinder and piston slidable therein, pressure reservoirs having outlets communicating with said cylinder at its end portions and inlets communicating with said source of fluid, valves in said inlets for regulating the flow of fluid into the respective reservoirs, vents in the wall of said cylinder adapted to be covered and uncovered alternately by said piston in its movement from end to end of the cylinder, and a detent yieldingly holding the piston in either of its extreme positions to permit the accumulation of fluid in one reservoir while the other reservoir is in communication with one of the said vents.

2. A pneumatically operated timing device comprising a cylinder, a dumb-bell piston slidable therein and having spaced heads, a pair of annular grooves formed in one of the heads, a detent extending through the wall of said cylinder and engageable in said grooves, alternately, when the piston reaches the ends of its stroke, a spring yieldingly forcing said detent into position to engage in said grooves, and a follower for varying the compression of said spring, a

source of fluid under pressure, and a pair of reservoirs communicating with such source of supply and with said cylinder at its ends, vents adjacent the ends of said cylinder each 5 of which is adapted to be opened when the piston is in the opposite end of the cylinder and is retained in such position by said detent, whereby the other vent will be closed by said piston and pressure will accumulate in 70 one of said reservoirs preparatory to returning the piston to the other extremity of its stroke while the other reservoir is being relieved of pressure through the opened vent, 10 means attached to the piston and extending 75 slidably through the end of the cylinder, for transferring the motion of the piston to a mechanism outside the cylinder.

15 3. A pneumatically operated timing device comprising a cylinder, a piston reciprocable therein, a source of fluid under pressure, reservoirs communicating with such source of fluid and with said cylinder to act 20 upon the piston and cause its reciprocation, a detent for yieldingly holding the piston in either of its extreme positions of movement, a pipe leading from the source of fluid to said cylinder but closed from communication 25 therewith by said piston in one extreme position of its movement, and a second pipe communicating with said cylinder and with mechanism to be actuated in time with the reciprocation of said piston, the piston in 30 the other of its extreme positions serving to establish communication between the source of fluid under pressure and said second pipe, together with means for venting said second pipe when such communication is disrupted.

35 4. A pneumatically operated timing device comprising a source of gas under pressure, a ported cylinder closed at each end, a piston rod reciprocable therein of which the central part is thinner than the ends, 40 forming a sliding, ported chamber between said ends and the cylinder walls, said chamber being out of connection with the space between the end of the cylinder and the end of the piston, means for applying gas pressure 45 on opposite ends of the piston for reciprocating it, inlet and outlet means for fluid to and from the said ported chamber, and valve means for regulating the flow of gas to the ends of said piston.

45 5. A pneumatically operated apparatus for imparting timed reciprocating motion to mechanism, comprising a cylinder, a rod-shaped piston reciprocable therein, having a pair of annular grooves formed near one 55 end, a detent extending through the wall of said cylinder and engageable in said grooves, alternately, when the piston reaches the ends of its stroke, a spring yieldingly forcing said detent into position to engage in said 60 grooves, and a follower for varying the compression of said spring, a source of fluid under pressure, and a pair of reservoirs communicating with said source of supply and with said cylinder at its ends, vents adjacent 65 the ends of said cylinder each of which is

adapted to be opened when the piston is in the opposite end of the cylinder and is retained in such position by said detent, whereby the other vent will be closed by said piston and pressure will accumulate in 70 one of said reservoirs preparatory to returning the piston to the other extremity of its stroke while the other reservoir is being relieved of pressure through the opened vent, 75 means attached to the piston and extending 80 slidably through the end of the cylinder, for transferring the motion of the piston to a mechanism outside the cylinder.

6. A pneumatically operated timing device comprising in combination with a source of fluid under pressure, a ported cylinder in communication therewith, a piston rod, of which the end portions are cylindrical and make a sliding fit with the cylinder, and of which the middle portion is of less thickness than the ends, thereby forming a ported chamber enclosed by the end portions of the rod, and the ported walls of the cylinder, said piston being reciprocable in said cylinder by the pressure of said fluid, means 85 for applying fluid pressure alternately on opposite faces of said piston for reciprocating it, valve means for regulating the flow of fluid to said cylinder, and rod means attached to the piston and extending slidably 90 through the end of the cylinder, for transferring the motion of the piston to a mechanism outside the cylinder. 95

7. A pneumatically operated timing device comprising a source of fluid under pressure, a ported cylinder and a piston slideable in said cylinder, pressure reservoirs in constant communication with the source of fluid and with said cylinder at its end portions, vents automatically opened and closed 100 by movement of the piston, whereby when one of said reservoirs is accumulating fluid from said source the other said reservoir is relieved of pressure by the opening of one 105 of the vents, and pressure responsive means for temporarily holding said piston at the ends of said cylinder during building up 110 of sufficient pressure in one reservoir to move the piston to the opposite end of the cylinder. 115

8. A pneumatically operated timing device comprising a ported cylinder, a piston reciprocable in said cylinder, a source of fluid under pressure, reservoirs in constant communication with said source of fluid and with said cylinder at its end portions, vents automatically opened and closed by movement of the piston to alternately relieve the reservoirs of accumulated pressure, 120 pressure responsive means for temporarily holding said piston at the ends of said cylinder during building up of sufficient pressure in one reservoir to move the piston to the opposite end of the cylinder, and mech- 125 130

anism actuated by reciprocation of said piston in time with its movements.

11. Means for automatically and independently controlling the time of movement of a piston in a cylinder from either of its extreme positions in the cylinder comprising a reservoir for each end of said cylinder, each of said reservoirs being in constant communication with the respective cylinder end to which it is connected and in constant communication through independently adjustable valves with a source of fluid under pressure, ports in said cylinder adapted to be opened by said piston dur-

ing its movement in the cylinder to discharge fluid from the cylinder, and means for yieldingly holding the piston in either of its extreme positions during building up of sufficient pressure in one of said reservoirs to move the piston to the other extreme position.

12. Means for automatically and independently controlling the time of movement of a piston in a cylinder from either of its extreme positions in the cylinder comprising a reservoir for each end of said cylinder, each of said reservoirs being in constant communication with the respective cylinder end to which it is connected and in constant communication with a source of fluid under pressure, ports in said cylinder adapted to be opened by said piston during its movement in the cylinder to discharge fluid from the cylinder and adjustable means for yieldingly holding the piston in either of its extreme positions during building up of sufficient pressure in one of said reservoirs to move said piston to the other extreme position.

13. A pneumatically operated timing device for controlling the flow of a fluid through a pipe comprising a pressure operated valve in said pipe, said valve being connected for pressure operation to a ported cylinder; a piston in said cylinder, a source of gas under pressure connected to said cylinder, and an exhaust port in said cylinder, said piston being adapted to alternately connect said pressure operated valve with said source of gas under pressure and with said exhaust port to operate the valve and means for automatically and independently controlling the time of movement of the piston in the cylinder from either of its extreme positions in the cylinder comprising a reservoir for each end of the cylinder, each of said reservoirs being in constant communication with the respective cylinder end to which it is connected and in constant communication through independently adjustable valves with a source of fluid under pressure, ports in said cylinder adapted to be opened by the piston during its movement in the cylinder to discharge fluid alternately from said reservoirs and means for yieldingly holding the piston in either of its extreme positions during building up of sufficient pressure in one of said reservoirs to move said piston to the other extreme position.

14. A pneumatically operated timing device for controlling the flow of a fluid through a pipe comprising a pressure operated valve in said pipe, said valve being connected for pressure operation to a ported cylinder, a piston in said cylinder, a source of gas under pressure connected to said cylinder, and an exhaust port in said cylinder, said piston being adapted to alternately 123

connect said pressure operated valve with said source of gas under pressure and with said exhaust port to operate the valve and means for automatically and independently controlling the time of movement of the piston in the cylinder from either of its extreme positions in the cylinder comprising a reservoir for each end of the cylinder, each of said reservoirs being in constant communication with the respective cylinder end to which it is connected and in constant

communication with a source of fluid under pressure, ports in said cylinder adapted to be opened by the piston during its movement in the cylinder to discharge fluid from the cylinder and adjustable means for yieldingly holding the piston in either of its extreme positions during building up of sufficient pressure in one of said reservoirs to move the piston to the other extreme position. 70 75
